UNITED STATES PATENT OFFICE.

JOHN WILLMAN WALVATNE, OF SHERMAN, SOUTH DAKOTA.

LIQUID-FUEL BURNER.

1,267,942.

Specification of Letters Patent. Patented May 28, 1918.

Application filed December 3, 1917. Serial No. 205,112.

To all whom it may concern:

Be it known that I, JOHN WILLMAN WALVATNE, a citizen of the United States, residing at Sherman, in the county of Minnehaha,

5 State of South Dakota, have invented certain new and useful Improvements in Liquid-Fuel Burners; and I do hereby declare the following to be a full, clear, and exact description of the invention, such as 10 will enable others skilled in the art to which it appertains to make and use the same.

This invention relates to improvements in burners and particularly to burners for burning kerosene or like oils.

15 The principal object of the present invention is to provide a device of this character which can be readily used in the fire-pot of a cook stove, especially in warm weather when it is not convenient or desirable to 20 build a wood or coal fire.

Another object is to provide a device of this character which is simple in construction, safe and easy in its operation, and which will give great heat while permitting 25 the lids of the stove top to be within the holes in the usual manner.

Other objects and advantages will be apparent from the following description when taken in connection with the accompanying 30 drawing.

In the drawing:

Figure 1 is a side elevation of my improved oil burner.

Fig. 2 is a top plan view of the same.

35 Fig. 3 is a longitudinal sectional view taken on the line 3—3 of Fig. 2.

Fig. 4 is a transverse sectional view taken on the line 4—4 of Fig. 2.

Referring particularly to the accompanying drawing, 10 represents a base on the ends of which are mounted the vertical uprights 11. Extending between these uprights and supported at its ends thereby, is a horizontal tubular chamber 12, the ends 45 being provided with the removable screw plugs 13 and 14 respectively. The former of these plugs, 13, is formed with a central longitudinal opening 15 in which is secured one end of the hollow oil conveying wire 16, 50 while the other end plug 14, is solid to prevent escape of oil through that end of the tube. On the base 10 is formed the pan 17, and in this pan is disposed a sheet of as-

bestos 18 which is adapted to be soaked in the oil and ignited for the purpose of heating the tube 12, as will appear more fully hereinafter.

Disposed longitudinally within the tubular chamber, and concentric therewith, is a solid metal bar 19 having the supporting 60 legs 20, said bar being adapted to provide additional heat radiating surface to vaporize the oil which flows into the chamber 12 through the wire 16. A hollow plug 21 is secured in the upper side of the tube 12 and 65 has an externally threaded nipple 22 on the side thereof for the detachable connection of a pipe 23 which is adapted to receive the gas generated in the tubular chamber 12. The pipe 23 extends laterally from the plug 70 21 and thence downwardly, the lower end being turned upwardly in a direction toward the central portion of the lower side of the chamber 12, and from this end of the pipe 23, as shown at 24, the oil which is vaporized, issues and is burned. The flame from the tip of the burner will strike the lower side of the chamber whereby said chamber will be properly heated and the oil which flows thereinto will be vaporized. 75 The other end of the wire 16 is connected to a pressure tank 25, containing the oil which is forced through the wire 16, into the chamber 12, and thence, in the form of gas, from the tip of the pipe 23.

80 The device is particularly adapted for use in connection with a cook stove, wherein it is not desirable to build a wood or coal fire, especially in the warmer weather, the burner and supporting parts being placed within 90 the fire-pot of the stove, and on the grate. The lids of the stove may then be replaced within the holes, a notch, not shown, being necessary in one edge of one of the lids, to permit the passage of the wire 16 therethrough. The tank may be placed at any 95 safe point adjacent the stove, while in operation.

From the above it will readily be seen that the device is extremely simple in construction, effective in operation, and can be manufactured at a comparatively low cost.

100 What is claimed is:

105 The combination with a pressure supply of liquid fuel, of a burner including a pan-shaped base, uprights at the ends of the base,

a horizontal vaporizing chamber supported by the uprights, a longitudinal heat retaining member within the chamber, a vertical pipe connected to the upper side of the chamber and extending therebelow and having its lower end turned upwardly in position to direct the flame therefrom against the lower side of the chamber, and oil con-

veying means between the said supply and one end of the said chamber. 10

In testimony whereof I affix my signature in the presence of two witnesses.

JOHN WILLMAN WALVATNE.
